[57] CLAIM

The ornamental design for a handle for a ratchet wrench, as shown and described.

DESCRIPTION

FIG. 1 is a bottom plan view of the handle for a ratchet wrench showing my new design;

FIG. 2 is a front elevational view thereof, the rear view being identical;

FIG. 3 is a cross-sectional view thereof, taken along the line 3—3 in FIG. 2.

FIG. 1

FIG. 2

FIG. 3
